Application June 28, 1950, Serial No. 10,788

Term of patent 7 years

(Cl. D86—8)

To all whom it may concern:

Be it known that I, Livia Mitchell, a citizen of United States of America, residing at 161 West 36th Street, in the county of New York and State of New York, have invented a new, original, and ornamental Design for a Comb, of which the following is a specification, reference being had to the accompanying drawing, forming part thereof.

In the drawing:

Fig. 1 is a front face view of a comb, showing my new design; and

Fig. 2 is a top plan view of a comb according to Fig. 1.

I claim:

The ornamental design for a comb, as shown.

LIVIA MITCHELL.
